UNITED STATES PATENT OFFICE.

MILLARD F. COX, OF RICHMOND, VIRGINIA, ASSIGNOR TO RICHMOND WORKS, OF RICHMOND, VIRGINIA, A CORPORATION OF VIRGINIA, AND THE AMERICAN LOCOMOTIVE COMPANY, OF NEW YORK, N. Y., A CORPORATION OF NEW YORK.

MUD-RING CORNER.

SPECIFICATION forming part of Letters Patent No. 688,064, dated December 3, 1901.

Application filed August 31, 1901. Serial No. 73,920. (No model.)

To all whom it may concern:

Be it known that I, MILLARD F. Cox, a citizen of the United States, and a resident of Richmond, Henrico county, Virginia, have 5 invented certain new and useful Improvements in Mud-Ring Corners, of which the following is a specification.

My invention relates to the fire-boxes of steam generators and boilers, and more especially to mud-rings employed in such generators or boilers as embody a water fire-box, wherein a mud-ring or "foundation-ring," as it is sometimes called, is employed to form the bottom of the water-space surrounding or in 15 contact with the fire-box; and my improvements are especially directed toward providing a construction of corner on the mud-ring which shall be more effective in sealing the fire-box against leakage, and thus obviate the serious difficulty heretofore encountered in all attempts to secure a steam and water tight joint at the corners of such mud-rings.

It is well-known in the art that constant trouble is experienced in the efforts to keep 25 the corners of the mud-ring tight, especially in locomotive-boilers or such other boilers as are subjected to the same necessary hard usage, and to which corners, owing to the conformation of the corner, when a drop-corner— 30 the most desirable form for this kind of boiler—it has been necessary to secure the inner and outer sheets or plates of the fire-box portion of the boiler by means of tap-bolts, with which bolts it has been found im- 35 possible to secure and maintain a perfectly tight joint. As a result of this construction it is only possible to utilize in the form of mud-ring heretofore commonly employed and familiar to those skilled in the art at the 40 best but three long rivets, one passing directly across the central part of the corner, with its inner head occupying the curved portion of the inner sheet at the corner, and one on each side thereof and having their inner heads in close contact with the head of the centrally-disposed rivet, while the outer heads of these long rivets are necessarily disposed about forty-five degrees apart. This 45 leaves a comparatively large extent of the

outer curved portion of the mud-ring free, 50 and this portion must be secured by tap-bolts to the outer sheets, which bolts cannot possibly effect and maintain a tight joint for any reasonable length of time. In order, therefore, to preserve all the advantages of a drop-corner and obviate the defects specified, I 55 provide a depressed or channeled corner on the mud-ring, so disposed as to permit the use of short rivets in lieu of tap-bolts, by which means I am enabled to use a sufficient 60 number of such rivets in sufficiently close proximity to one another to effectively secure a perfectly tight joint and one which will stand the heavy strains and stresses to which the corners are subjected in use, especially 65 on locomotive and like boilers.

With the foregoing objects in view, therefore, my invention consists in a novel construction of mud-ring corner and in the details thereof, as hereinafter described and 70 claimed, with reference to the accompanying drawings, in which—

Figure 1 is a sectional plan view showing a mud-ring according to my invention applied to the bottom of a fire-box. Fig. 2 is a broken 75 sectional side elevation of one of the corners. Fig. 3 is a vertical sectional detail view through a corner, and Fig. 4 is a similar view of a modification.

Referring now to the drawings, in which the 80 same reference characters relate to the same or corresponding parts in all the views, the numeral 1 indicates the outer sheet or plate of a fire-box forming with the inner sheet or plate 2 the water-space around the fire-box 85 3. These plates are bent on a suitable radius to form the curved corners 4, the inner plates being united by a lap-joint 5, in which one of said plates is of normal cross-section, as at 6, overlapping the other of tapered cross-section, as at 7, thus forming a continuous inner surface, while the outer plates are united together in a similar manner, as shown at 8 and 9, respectively.

The numeral 10 indicates a solid or drop 90 mud-ring shaped to accurately fit the inner surfaces of the outer and inner plates. This ring may be milled or drop-forged or made of

cast-steel or a combination of cast-steel ends and wrought-iron sides, and at the corners it is depressed or channeled, as indicated at 11, where the depression is shown of such depth, width, and length as will accommodate the rivet-heads of short rivets 12, the inner heads of which can be readily formed by any suitable rotating device.

It should be observed that the provision of 10 the depression 11 does not materially weaken the ring, and therefore my improved ring possesses all the advantages of the drop-corner and the further advantage of capability of use in any mud-ring of ordinary width in which 15 the drop-corner is inapplicable. Furthermore, it will be evident that my improved mud-ring corner dispenses entirely with the long rivet commonly used directly across the corner, such long rivet being replaced by the 20 two oppositely-disposed short rivets 12.

As a further means of securing the corner I may employ tap-bolts 13 above the depression 11, such bolts alternating with a few of the short rivets and with the long rivets 14, 25 which pass across the extreme limits of the corner, and thus disposed at substantially right angles to each other.

With my construction it will be seen that the joints at the corner are made effectively 30 steam and water tight and that the short rivets provide a more desirable and effective means for binding the plates to the corners of the ring.

I may in many cases entirely dispense with 35 tap-bolts by the use of a construction as shown, for example, in the modified form of mud-ring corner illustrated in Fig. 4, where the corners are thickened on top. The thickened portions 15 form a close joint with the 40 plates.

I am aware that a sectional mud-ring has been proposed in which corrugations are employed and that such rings have been channeled to lighten them, in which cases the 45 rings are weakened to such an extent as to render them ineffective for practical purposes. I am also aware that it has been proposed to provide in such sectional ring flanges at the corner of the steam-space, in which 50 construction the ring is by such means so re-

duced in strength as to be impractical for use as a mud-ring.

I claim as my invention—

1. The herein-described mud-ring for boilers, consisting of a solid ring adapted to fit 55 the space around a fire-box, and having depressions of limited extent at the corners, in combination with the plates of the boiler at the corners, and short rivets passing through the plates and having their upset heads projecting into said depression, substantially as described.

2. The herein-described mud-ring for boilers, consisting of a solid ring adapted to fit 65 the space around a fire-box, and having depressions of limited extent at the corners, in combination with the plates of the boiler at the corners, and short rivets passing through the plates and having heads projecting into said depression, two of said short rivets being disposed opposite to each other across the 70 corner, thereby dispensing with a long rivet at this point.

3. The herein-described mud-ring for boilers, consisting of a solid ring adapted to fit 75 the space around a fire-box, and having depressions of limited extent at the corner, in combination with the plates of the boiler at the corner, and short rivets passing through the plates and having heads projecting into 80 said depression, said ring being thickened on one side, at the top, substantially as described and for the purposes set forth.

4. As a new article of manufacture, a solid mud-ring for boilers, having rounded corners 85 and provided with depressions of limited extent at the corners on one side of the ring, such depressions being of such shape and dimensions as to receive and accommodate the heads of rivets passing through the walls of 90 the ring in proximity to said depressions, substantially as described.

In testimony whereof I have signed my name to this specification in the presence of two subscribing witnesses.

MILLARD F. COX.

Witnesses:

LESLIE H. JONES,
ALBERT O. BOSCHEN.

It is hereby certified that the assignee in Letters Patent No. 688,064, granted December 3, 1901, upon the application of Millard F. Cox, of Richmond, Virginia, for an improvement in "Mud-Ring Corners," should have been described as *Richmond Works, of Richmond, Virginia, a corporation of Virginia, of The American Locomotive Company, of New York, N. Y., a corporation of New York*," instead of "Richmond Works, of Richmond, Virginia, a corporation of Virginia, and The American Locomotive Company of New York, N. Y., a corporation of New York;" and line 82, page 2, the word "at" should read *as*; and that the said Letters Patent should be read with these corrections therein that the same may conform to the record of the case in the Patent Office.

Signed, countersigned, and sealed this 10th day of December, A. D., 1901.
